Patented Dec. 23, 1924.

UNITED STATES PATENT OFFICE.

ERNEST JOSEPH PERRY, OF BIRMINGHAM, ENGLAND.

TUBE OF AXMINSTER AND LIKE CARPET LOOMS AND METHOD OF THREADING THE SAME.

Application filed October 11, 1922. Serial No. 593,838.

To all whom it may concern:

Be it known that I, ERNEST JOSEPH PERRY, subject of the Kingdom of Great Britain, residing at 68 Heathmill Lane, Birmingham, in the county of Warwick, England, manufacturer, have invented certain new and useful Improvements in or Relating to the Tubes of Axminster and like Carpet Looms and Methods of Threading the Same, 10 of which the following is a specification.

This invention comprises certain improvements in or relating to the tubes of Axminster and like carpet looms, and to the method of threading the same.

15 In Axminster carpet looms as hitherto in use, the tubes, which are ordinarily of a tapering seamless metal construction and are mounted in projecting parallel series on a "stick" disposed transversely in front of and in parallel relation to the bobbin, have been threaded either manually or mechanically by inserting the extreme ends of the threads axially into the inner ends or eyes of their respective tubes, and passing them straight through the bores thereof and out at the outer ends.

20 The present invention has for its purpose the provision of tubes of such improved construction as to permit of an improved and simplified method of threading, which method consists in simply drawing the threads forwardly over the curved rear face of the stick and over the inner ends or eyes of the tubes, without the necessity of passing the extreme ends of the threads into the eyes of the tubes.

25 For this purpose the invention consists essentially in forming each tube with a longitudinal slit through which the thread is adapted to be passed into the bore of the tube whilst being thus forwardly drawn over the inner end or eye of the tube. Advantageously said slit is formed in one of the upright sides of the tube, the upper edge of the eye of the tube having a lateral inclination towards the mouth of the slit to serve as a guide thereto. A further feature consists in making the slit of a undulatory form to further facilitate the entry of 30 the thread into the tube and to minimize its liability to accidental displacement therefrom.

In order that this invention may be clearly understood and readily carried into practice, reference may be had to the appended

explanatory sheet of drawings, upon which:—

Figure 1 is a sectional side elevation of the tubes and stick in operative relation to the bobbin, and illustrating the longitudinal 60 threading slit in the tube in accordance with the invention.

Figure 2 is a fragmentary perspective view of the stick carrying the longitudinally slotted tubes. 65

Figures 3 to 6 are detail views of the tube detached, Figure 3 being a side elevation, Figure 4 being an inner end elevation, Figure 5 being an outer end elevation, and Figure 6 being a plan. 70

Figure 7 is a plan of the blank from which the tube shown in Figures 1 to 6 is formed.

In a preferred embodiment of the invention the tube *a* is of a tapering sheet metal construction, advantageously formed from a suitably shaped blank *a*¹ (Figure 7), and of the ordinary pippin-shaped cross section. The two longitudinal sides *a*² *a*³ of the sheet metal blank are of an undulatory and complementary form, and the blank is bent or folded into the desired tubular formation in such a manner that said complementary undulatory edges provide a narrow undulatory slit *a*⁴ extending from one end to the other 85 of one of the upright sides of the tube. The inner end or eye of the tube is of substantially rectangular form in end elevation, see Figure 4, and its upper edge *a*⁵ is laterally and forwardly inclined towards the mouth 90 *a*⁶ of the slit, which mouth *a*⁶ is somewhat widened or expanded vertically, with an inclined and rounded shoulder *a*⁷ at its lower edge, the laterally inclined upper edge *a*⁵ cooperating with the inclined and rounded 95 lower shoulder *a*⁷ to provide a means of guiding the thread *b* into the mouth of the slit, which mouth *a*⁶ is so disposed as to take advantage of the natural tendency of the threads *b* to pass between the tubes *a* in 100 being drawn forwardly thereover. The undulatory slit *a*⁴ may at its outer end be either downturned as shown in the drawings, or upturned, according to the type of tube to which the invention is applied. 105

To thread the tubes *a*, the threads *b* are simply drawn forwardly from the bobbin *c* over the curved rear face *d*¹ of the stick *d* and over the inner ends or eyes of the tubes, this action causing the threads to be guided 110

through the slits a^4 of their respective tubes into their working positions therein.

The tubes a as thus constructed are adapted for threading by the improved method 5 either individually or simultaneously. In the latter case, the ends of the threads b on the bobbin are spaced and secured within a 10 comb and sheath device of known form, consisting of a sheath of U-section and a comb jointed in knife-blade form thereto, this 15 comb and sheath device enabling the entire series of threads b to be simultaneously drawn over the rear face of the stick d and over the inner ends or eyes of the tubes a , in the necessary spaced relation, to permit of 20 the threads being passed into the slits a^4 of their respective tubes.

What I claim as my invention and desire to secure by Letters Patent is:—

20 1. A carpet loom tube having a longitudinal

slit in one of the upright sides of the tube, and also having a vertically widened mouth of substantially rectangular cross section at the eye end, the upper side of said mouth presenting a laterally inclined edge, 25 which leads to said slit to serve as a guide thereinto.

2. A carpet loom tube having a longitudinal slit in one of the upright sides of the tube, and also having a vertically widened mouth of substantially rectangular cross section at the eye end, the upper side of said mouth presenting a laterally inclined edge, 30 spaced from the inner end of the tube, which leads to said slit to serve as a guide thereinto. 35

In witness whereof I have hereunto set my hand.

ERNEST JOSEPH PERRY.
